CANDLESTICK SET

Julie C. Swobe, Berkeley, Calif.

Application January 30, 1934, Serial No. 708,975

2 Claims. (Cl. 67—23)

This invention relates to a candlestick set or chandelier composed of separable candlesticks which may be grouped to form chandeliers of varying ornamental formations.

5 The object of the present invention is to provide a candlestick set or chandelier composed of a plurality of individual candlesticks which may be separated for individual use or nested and grouped to form varying ornamental configurations. The invention, briefly stated, comprises a plurality of candlesticks of varying length which may be polyhedral, cylindrical, or otherwise shaped, and which are cut or grooved on one side to fit the contour of an adjacent candlestick 10 15 so that a number of candlesticks may be assembled and nested with relation to each other to form chandeliers of varying ornamental formations.

The invention is shown by way of illustration 20 in the accompanying drawings, in which—

Fig. 1 is a perspective view showing three candlesticks adapted for nesting and grouping purposes.

Fig. 2 is a plan view of the candlestick shown 25 in Fig. 1 showing the manner in which the candlesticks nest against each other.

Fig. 3 shows one possible grouping of the type 30 of candlesticks shown in Fig. 1.

Fig. 4 shows another grouping.

35 Fig. 5 shows still another grouping.

Fig. 6 shows a grouping of a polyhedral form 40 of candlestick. In this instance they are of hexagonal cross section and they are grouped to nest against each other.

Fig. 7 shows one method of nesting.

Fig. 8 another method of nesting.

Fig. 9 is a perspective view showing a candlestick which is square in cross section.

Fig. 10 shows how they nest.

45 Fig. 11 is a plan view showing a candlestick of triangular cross section and the manner in which they nest.

Referring to the drawings in detail, particularly Figs. 1 and 2, it will be noted that the candlesticks, indicated at A, B and C, are of cylindrical cross section. They are elongated and vary in length. One side of the candlesticks, shown at B and C, is cut away or grooved from end to end to fit the contour of an adjacent 50 candlestick, thus permitting the candlesticks to be nested and grouped as shown in Figs. 2, 3, 4, and 5. Wherever a group formation is formed one candlestick need not be grooved, for instance the one indicated at A, but the others must be 55 grooved to permit nesting against each other.

In Fig. 3 a series of candlesticks of cylindrical type are shown grouped in one formation. In Figs. 2 and 4 they are shown as separated in two groups, and in Fig. 5 they are separated in two groups with a single candlestick between them.

The cross section of the candlestick is more or less immaterial, as shown in Figs. 6 to 11, inclusive, that is, they may be polyhedral in shape, a hexagonal form being shown in Figs. 6, 65 7 and 8; a square form in Figs. 9 and 10, and a triangular form in Fig. 11. Other shapes are, of course, possible. Regardless of the cross sectional shape, it is preferable that the candlesticks be of varying length to form the step formation shown in different groups, and it is also desirable that the grooves indicated at 2 and formed in one side, as shown in Fig. 1, should be of a contour so that snug nesting is possible.

In Figs. 9 and 10 the groove is indicated at 3. 75 Here it is of a different shape than that shown in Fig. 1, but the shape is nevertheless such that it fits the contour of an adjacent candlestick and thereby permits nesting; the same being true of the hexagonal type shown in Figs. 6 to 8, or the 80 triangular type shown in Fig. 11.

The candlesticks when grouped form a chandelier and varying formations and artistic and ornamental effects can be produced by the variation in grouping and by the particular shape of 85 candlestick employed. A candlestick set of this character lends itself for table and mantel decoration as the candlesticks may be arranged in groups longitudinally of the table or mantel and they may obviously be separated and spaced 90 apart as conditions may demand.

In each instance the candlestick will have a socket 4 formed in the upper end for the reception of a candle. This socket may be tapering, or otherwise, in form, depending upon the type 95 of candle to be supported, and while this and other features have been more or less specifically described, I wish it understood that various changes may be resorted to within the scope of the appended claims. Similarly, that the materials and finish of the several parts employed 100 may be such as the manufacturer may decide, or varying conditions or uses may demand.

Having thus described my invention, what I claim and desire to secure by Letters Patent is— 105

1. An article of manufacture comprising a candlestick set including a plurality of elongated candlesticks substantially similar in cross section but varying in length, all of the candlesticks, except the longest one, having a groove formed in one 110

side and extending from top to bottom thereof, and said grooves being shaped to fit the contour of an adjacent candlestick to permit the candlesticks to nest one into the other.

5 2. An article of manufacture comprising a candlestick set including a plurality of elongated candlesticks substantially similar in cross section but varying in length, all of the candlesticks, except

the longest one, having a groove formed in one side and extending from top to bottom thereof, and said grooves being shaped to fit the contour of an adjacent candlestick to permit the candlesticks to nest one into the other, said candlesticks being separable and adjustable to stand independently to permit grouping in varying forms.
